UNITED STATES PATENT OFFICE.

ELMER O. EDWARDS, OF ST. PAUL, MINNESOTA, ASSIGNOR OF ONE-HALF TO ANDREW NOREN, OF ST. PAUL, MINNESOTA.

SANITARY CLOSET-SEAT.

1,076,107.

Specification of Letters Patent.

Patented Oct. 21, 1913.

Application filed December 23, 1912. Serial No. 738,224.

To all whom it may concern:

Be it known that I, ELMER O. EDWARDS, a citizen of the United States, residing at St. Paul, in the county of Ramsey and State of Minnesota, have invented a new and useful Sanitary Closet-Seat, of which the following is a specification.

My invention relates to improvements in closet seats, and the object is to provide a sanitary closet seat of such construction that each person using it may sit on a clean surface and not have to come in contact with a seat surface which may have been rendered unclean by disease or otherwise from previous use by some other person.

In carrying out this idea I provide a supply of exchangeable paper sheets, each provided with an aperture corresponding to the aperture in the seat, and so arranged that only one sheet at a time is accessible for sitting on and is readily exchanged and replaced by a clean sheet; preferably the exchange is effected by a mechanism which is operated automatically by the raising of the solid cover of the seat preparatory to occupying the seat.

In the accompanying drawings, Figure 1 is a top view of a closet embodying my invention; in said view the cover or upper portion of the mechanism chamber is removed and a portion is broken away as on the line *b*—*b* Fig. 2. Fig. 2 is a vertical section on the line *a*—*a* Fig. 1. Fig. 3 is an enlarged and more completed side elevation of Fig. 1 with the outer side wall of the mechanism chamber removed and the toothed sector 15 shown at the outer side of the gear wheel 43, while in Fig. 1 it is at the inner side, thus showing that it may be placed in either position. Fig. 4 is a partly sectional enlarged end view of the roller 25 and pinion and ratchet mechanism on one end of it. Fig. 5 is a section on the line *c*—*c* Fig. 4 including also fragments of the frame work of the seat and the skeleton cover of same in which the roller is journaled. Fig. 6 is a partly sectional side elevation only sufficiently completed to show a modification of the paper moving mechanism. Fig. 7 is a bottom edge view of the sector 15 in Fig. 3 on a reduced scale.

Referring to the drawings by reference numerals, 1 designates the bowl of the closet and is provided with two posts, 2, in which is journaled a shaft 3. Pivottally mounted on

said shaft are the hinge members 4 of the seat 5. Said seat is supported on the bowl by legs 6 having rubber tips 7 so as to create sufficient space between the bowl and the seat for the chamber or inclosure 8 and the rollers 9 and 10 mounted therein and extending across the bowl below the rear end of the seat.

Fixed at 11 on the shaft 3 are two hinge members 12, to which the solid cover 13 of the seat is secured at 14, so that when the cover is raised or lowered the shaft will make fully one-fourth of a revolution and will thereby swing a toothed sector 15, which is fixed on the shaft and operates a paper-moving mechanism which will presently be further described.

Although the seat and all parts involved in it as a seat are usually more or less oval, they may for convenience of description be herein referred to as "ring-shaped;" it will then be seen that the seat is composed of a ring-shaped body 5 having at its base an inward flange 5^a, upon which is mounted a series of springs 16, which support a flat ring-shaped plate 17, upon which a pile of ring-shaped paper sheets 18 is supported and fed upward by the springs as fast as the pile is reduced by removal of one sheet at a time from its top. Said upward movement of the paper pile is limited by a keeper consisting of a flat ring 19 having a downward rim 20 passing partly downward about the body of the seat, and is there locked by catches like 21 in Fig. 3 engaging in dents 22 in the seat; or any other suitable catches may be employed. Said keeper is hinged to the seat at 23, and is provided with journal bearings 24, in which rotate the ends of the roller 25, said roller extending across the keeper and through a transverse slot 26 near the rear end of same contacts with the upper side of the uppermost sheet of paper of the pile 18. In Fig. 5 it will be seen that the roller is enlarged near the ends by rubber coverings 25^a which are the only portions of the roller to engage and move the sheet; this is to avoid the middle of the roller moving the next sheet below while the ends of the roller move away the topmost sheet.

As best shown in Figs. 3, 4, 5 and 7, the roller 25 has at one end fixed a ratchet wheel 27 engaged by a pawl 28, which is pivoted at 28^a to a disk 29 having a rim 30 by which

to house and protect the ratchet mechanism; 31 is a spring arranged to hold the pawl engaged with the ratchet wheel. The disk 29 is retained on the shaft by a pin 33; and 5 fixed in concentric position to the disk is a small gear wheel 34 and a hub 35, the latter having at one side a flat face 36 (see Figs. 3 and 4) adapted to be engaged by the smooth cam-edge 37 (shown in Figs. 3 and 10 7) of the sector, for a purpose presently to be described. Mounted on a stud, or it may be a small shaft, 38, in the mechanism chamber 39, which may be secured to the seat as at 40 in Fig. 3, rotates a pinion 41, which 15 is in constant mesh with the longer segmental rack 42 of the sector; and fixed to said pinion is a gear-wheel 43, which is in constant mesh with a pinion 44, fixed on one end of the roller 9. Said roller 9 and 20 the roller 10, are covered with rubber so as to take a firm hold of the paper 18^a and by coaction at both sides thereof pull the paper into the bowl. The paper does, however, not reach said pair of rollers until the roller 25 has acted on the top sheet of the pile and 25 moved rearwardly and downwardly between the guides 45, 46, (shown in Fig. 2).

In Figs. 1 and 2 is shown that the cover 13 rests on its short rubber cushions 47 and 30 is provided with a flat broad tooth, 48, having a lateral cavity 49 adapted to engage a spring catch 50, arranged in a pocket 51 in the front end of the seat; said catching means holding the seat and the cover together against accidental separation during the raising and lowering of the seat for purpose of using the bowl as a urinal; but if only the cover is to be raised it is taken hold of and raised while the seat will by 35 its own weight be kept down, the spring catch yielding for said weight. 52 is a peg fixed in the front end of the seat and engaging all the paper sheets 18, the sheets having either a hole (not shown) for the 40 peg, or, as in the present illustration, a 45 notch 53 in which the peg engages.

In Fig. 2 54 is a guard to prevent the paper 18^a crowding too much forward in the bowl while passing into it. In Figs. 3 and 50 55 is a slot in one side of the mechanism chamber 39 for the shaft of the roller 25 to move up and down in when the keeper 19 is raised for purpose of placing the paper 18 into the seat.

55 In the operation of the device, the paper 18 having been placed in the seat, as just described, a person wishing to use the bowl without the seat takes hold of the seat and raises it to a slightly rearwardly inclined 60 position against a suitable support (not shown), and when through he likewise folds down the seat, the paper keeper, and the cover 13 without separating any of them. But if he wishes to make use of the seat, he 65 takes hold of the cover 13 only, and by rais-

ing it to the usual standing position he turns the shaft 3 and thereby causes the sector portion 42^a to rotate the paper-starting roller 25, and after said roller has moved the upper sheet of the pile 18 into engagement between the rollers 9, 10, which rollers rotate much faster than the roller 25, the latter roller is rotated by its contact with the moving paper, so fast that its ratchet wheel 27 must rotate with its teeth playing under the pawl 28; this would be necessary even if the pinion 34 was turning at its normal speed, but especially now when it is standing still, the cam 37 holding it still so that the rack 42^a, which has passed the pinion, will 70 find it in position for engagement when it returns to it. The operator has thus by raising the cover automatically removed the top sheet of the paper supply, and he can sit on the clean sheet found next below it. When 75 he closes the cover again the rollers 9, 10 reverse their rotation, and as the sector portion 42^a reaches the pinion 34, it rotates it backward to normal position, the pawl 28 playing on the teeth of the ratchet wheel, 80 so as not to turn the roller 25; everything is now ready for the next operation, in which raising of the cover removes the next sheet of paper, and so on, as just described, for 85 each person making use of the seat, until the supply of paper is exhausted, when the keeper or paper-retaining ring 19 is raised and a new supply of paper placed in the seat. As each sheet of paper is pulled away by the rollers and passed down into the 90 bowl it is forced away from the peg 52 either by tearing it away or by pulling it tightly between the top of the peg and the paper keeper adjacent thereto.

In the modification shown in Fig. 6 the 105 starting roller 25 is the same as in the other views, it having the same ratchet arrangement, the disk 29, and the pinion 34 engaged by the sector 15; but when the paper is started by the roller 25 it is soon caught between that roller and the adjacent roller 25^x and is thus moved along as 18^a, guided only by a single guide 45. This is one of the many modified ways in which the paper may be moved into the bowl. Another modification, which needs no illustration, as it is obvious to any mechanic, is that if so desired a slight change in the paper moving mechanism will enable the cover to move the paper while it is being folded down, instead of 110 while it is being raised.

115 What I claim is:

1. In a closet of the class described, the combination of a bowl, a seat hinged to rest upon the bowl and adapted to contain a 125 pile of sheets of paper having an opening in the middle and arranged to form the top of the seat, a cover hinged to fold upon the seat, and means automatically operated by the motion of the cover on its hinges where- 130

by the uppermost sheet of the paper pile is removed into the bowl.

2. In a closet of the class described, the combination of a bowl, a seat hinged to rest upon the bowl and adapted to contain a pile of sheets of paper, a supply of paper contained in said cover and arranged with the uppermost sheet as the surface of the seat to sit on, automatic means for raising the supply of paper to said position as fast as the supply is diminished by removing sheets from the top thereof; a cover hinged to fold upon the seat, and a mechanism actuated by the motion of the cover whereby each motion of the cover removes the uppermost sheet of the supply and passes it into the bowl.
3. In a closet of the kind described, the combination of a bowl, a seat hinged to fold upon the bowl and adapted to hold a pile of paper sheets in position for sitting on same, a cover hinged to fold upon the seat, and means operated by the motion of the cover at its hinges whereby one sheet at a time is removed from the top of the pile of sheets.
4. In a closet of the kind described, the combination of a bowl, a seat hinged to fold

upon the bowl and adapted to hold a pile of sheets of paper for a person to sit on, a cover hinged to fold upon the seat and the paper contained in the same, means for holding said seat and its cover connected in parallel position against accidental separation, and means operated by the motion of the cover at its hinges whereby one sheet at a time is removed from the top of the pile of sheets.

5. In a closet seat of the kind described, the combination of a bowl, a seat hinged to fold and rest upon the bowl, a pile of sheets open in the middle held by the seat to form its top, a cover hinged to rest upon the seat, a toothed sector operated by the motion of the cover, and rollers rotated by the sector and arranged to act on the paper to remove each top sheet thereof into the bowl.

In testimony whereof I affix my signature, in presence of two witnesses.

ELMER O. EDWARDS.
